UNITED STATES PATENT OFFICE.

FRANK O'NEILL, OF DETROIT, MICHIGAN.

BOTTLE-FINISHING MACHINE.

No. 805,877.

Specification of Letters Patent.

Patented Nov. 28, 1905.

Application filed July 13, 1905. Serial No. 269,538.

To all whom it may concern:

Be it known that I, FRANK O'NEILL, a citizen of the United States, residing at Detroit, in the county of Wayne and State of Michigan, have invented certain new and useful Improvements in Bottle-Finishing Machines, of which the following is a specification, reference being had therein to the accompanying drawings.

This invention relates to apparatus for finishing bottles, and has particular reference to an adaptation for such use of the apparatus shown and described in my application, Serial No. 229,473, filed October 21, 1904. The invention as embodied in that application is designed primarily for finishing tumblers and similar objects, and while the underlying principles thereof are available for finishing bottles as well as tumblers, yet the specific embodiment of the operating parts is necessarily different for the two uses, and hence the primary object of the present invention is to so change the mechanism of the former application, without disturbing the underlying principles thereof, as to adapt it for bottle-finishing use.

A further object is to provide bottle-neck-finishing devices of improved construction and to provide for moving a series of such devices into operative position successively, thus presenting a fresh device for each finishing operation.

The invention further contemplates an improved snap or holder for sustaining bottles while being finished.

A further object is to provide for resisting undue pressure of the formers on the reheated and softened glass by admitting air under pressure into the bottle during the finishing operation.

In the accompanying drawings, Figure 1 is a vertical sectional view of the apparatus, the left-hand side of the figure being taken in the plane of the finishing mechanism and illustrating the positions of the several parts during the finishing operation. Fig. 2 is an enlarged sectional view of a portion of one of the finishing devices. Fig. 3 is a side elevation of the opposite side of the upper portion of the machine from that shown in Fig. 1. Fig. 4 is an edge view, and Fig. 5 a vertical sectional view, of said upper portion. Fig. 6 is a diagrammatic plan view. Fig. 7 is a sectional view of the reheating-hood and a portion of the carrier, also one of the bottle-holders. Fig. 8 is a detail view of the bottle-hold-

ing snap. Fig. 9 is a similar view of the spring-latch device for actuating the carrier of the finishing mechanism.

Referring to the drawings, 2 designates the base, and 3 the central upright, of the machine-frame, and rising from the latter is hollow post 4. Secured to the post is bearing 5, and rotatable thereon is the horizontal ware carrier or table 6. Above the table is a circular series of bottle-holders or snaps, each of which is mounted on a vertically-movable shaft 14, and beneath and rotatable with the table is mechanism for rotating the shafts at either low or high speed, also mechanism for raising and lowering the same. Each of these under mechanisms consists of a frame 15, provided with a vertical bearing 15', and journaled in this bearing is tubular hub 16, carrying the large horizontal gear-wheel 17 and the relatively small gear 18. Journaled in frame 15 is a horizontal shaft 19, and rotatable on the outer portion of this shaft is gear 20, meshing with gear 18, and a gear 21, meshing with gear 17. A double clutch device 22 is arranged between gears 20 and 21, which is adapted to engage the same interchangeably for driving spindle 14 at either low or high speed, said device being operated by lever 23. The latter carries roller 24, which rides on the under face of cam-ring 25, being held in engagement therewith by spring 26, all as in my application above referred to. The inner end of shaft 19 is geared to wheel 27, journaled on post 4, said gear being driven by the short vertical shaft 28, the latter being geared to the main horizontal drive-shaft 29.

For moving shaft 14 vertically for the purpose of raising and lowering the bottle-holder the lower portion of the shaft extends through frame-guide 15", with a spring 31 confined on the lower portion of the shaft for holding it normally depressed. A bell-crank lever 32 is fulcrumed to the lower portion of frame 15, one arm thereof having a link connection with the lower end of shaft 14 and the other arm carrying roller 34, which rides on the outer face of the oscillating cam-ring 35, the latter being supported by the circular vertical extension 2' of the frame.

The bottle-holder or snap at the upper end of shaft 14 consists of a head or base 36, upon which the bottle rests, and hinged thereto at their lower ends are the bottle-clamping segments 37. Linked to each of these segments is a weighted lever 37', fulcrumed to arm 36' of base 36. When shaft 14 is being driven

by the slow gear, as it is throughout the revolution of the carrier excepting when at the finishing position, the centrifugal force is not sufficient to raise the weighted arms and cause 5 segments 37 to clamp the bottle. This clamping hold is necessary only during the finishing operation, at which time shaft 14 is rotated by the high-speed gears 18 and 21 when the speed attained is sufficient to raise the 10 weighted arms and cause the segment-plates 37 to tightly clamp the bottle, causing the latter to rotate therewith in direction opposite to the finishing mechanism, as will presently appear.

15 The finishing mechanism is supported by a frame or bracket 38, extending laterally from post 4. Projecting from the outer lower portion of this frame is a spindle 39, and rotatable thereon is a wheel-like carrier 40. Each 20 of the four radial arms of this carrier supports a finishing mechanism which are turned downward successively into operative position in line with the bottle-holders, carriers 6 and 40 being advanced intermittently at the 25 same time, so that a fresh finishing mechanism is presented as each bottle is moved to the finishing position.

For imparting a quarter-turn to carrier 40 an arm 41 is adapted to turn on spindle 39 and 30 carries a beveled spring-latch 42, which successively engages notches 40' in the hub of carrier 40, the latch being arranged to move backward freely, but to interlock with one of said notches when moving forward. For 35 oscillating arm 41 a link 43 extends to crank 44 on one end of the horizontal rock-shaft 45, journaled in frame 38. At the opposite end of the rock-shaft is the short arm 46, connected by a link 46' with vertical rod 47, the 40 latter being slidable in guides on frame 38 and held normally depressed by coiled spring 47'.

For operating the several parts of the finishing mechanism a tubular shaft 48 and a solid shaft 49 are extended upward through 45 post 4, said shafts, respectively, being driven at their lower ends from shaft 28 by gearing 48' and 49'. Secured to the upper end of tubular shaft 48 is the disk-like wheel 50, having on its lower face the depending cam-like 50 projection 51 and on its top face a corresponding projection 52. Spring 47' holds rod 47 raised, with roller 47" at the upper end thereof pressed upward against the under face of disk 50. When, however, the latter is so rotated 55 as to move projection 51 over the roller and depress rod 47, the downward movement thereof operates to rock shaft 45 and to move the parts connected thereto into the position indicated in dotted lines in Figs. 1 and 3, thus 60 advancing carrier 40 a quarter-turn and placing a fresh finishing mechanism in operative position. As soon as projection 51 passes rod 47 the latter is raised by the spring and the parts operated by it are restored to the full- 65 line positions indicated in Fig. 1 and in posi-

tion to impart the next quarter-turn to the finishing-mechanism carrier.

Each of the four finishing mechanisms consists of a stem or shaft 53, rotatably secured in carrier 40 and at its outer end carrying a 70 plug 54 for the interior of the bottle-neck. Also carried by stem 53 is a head 55, and hinged thereto are the radially-arranged exterior neck-formers 56, four being here shown. Links 57 connect these hinged formers with 75 head 58, slidable on the inner portion of stem 53, and a spring operating on the stem between heads 55 and 58 holds the latter normally pressed inward or toward carrier 40, with formers 56 open. Plug 54 and formers 80 56 may be variously shaped as required for imparting the required shape to the interior and exterior of the bottle-neck.

Secured to the inner extremity of each stem 85 53 is a friction-wheel 59, and as each of the finishing mechanisms is turned downward into operative position this wheel is placed in engagement with the constantly and rapidly rotating wheel 60, carried by the lower end of vertical shaft 61, journaled in the outer portion of frame 38. This shaft is driven by a belt 62, extending from a pulley carried by the 90 upper extremity of shaft 49.

Slidable on one side of frame 38 is the bar 63, having at its lower end a roller 63', which 95 operates upon the depression of the bar to depress head 58 of the operative finishing mechanism, and thereby close and hold closed formers 56 around the bottle-neck being operated upon. Bar 63 is raised and lowered by 100 means of a lever 64, fulcrumed to frame 38. The outer end of this lever is forked, as indicated at 64', with shaft 61 extending therethrough. One fork of the lever is connected by a link to lateral extension 63" of bar 63, and the other fork is similarly connected to a collar 65, slidable on a rod 66. This rod is movable 105 vertically in guides projecting from frame 38 and is held normally raised by the spring 67, but is adapted to be depressed by the downward movement of the lever, the cushioning-spring 67' being placed on the rod between collar 65 and stop 66', fixed to the rod. At the lower end of the rod is an upwardly-recessed head 66" for engaging the plug 54 of the upturned finishing device, thereby firmly holding the entire finishing mechanism and maintaining the active downwardly-disposed device in proper alinement. Bar 63 and rod 66, with lever 64, are normally in raised position. For depressing the same the rear end of the lever is connected by a link 64' to a vertical rod 68, similar to rod 47, but held normally depressed (with the outer portion of the lever raised) by a spring 68'. At the upper 115 end of said rod is a roller 68", which overhangs disk 50 and is adapted to be raised at the proper interval by projection 52 passing therebeneath.

Ring 35 is of concentric form, except for 120

- bulge 35', which in length is a little shorter than the distance between the lever-tilting rollers 34, the arrangement being such that when the ring is oscillated this bulge is moved forward and backward across the radial line of the finishing mechanism. For advancing carrier 6 step by step an oscillating arm 69 is employed, which may be operated in any suitable manner. As ring 35 requires an oscillating movement similar to arm 69, I connect said parts by providing the ring with a projecting arm 70, which is connected by rod 70' with a depending extension 69' of the outer end of arm 69. Arm 69 having advanced table 6 in the direction indicated by the left-hand arrow in Fig. 6, said arm reaches the limit of its movement, which is indicated by the full-line position in said figure. Then as the arm advances to the position indicated in dotted line for securing a hold for the next advancing movement it moves with it ring 35, causing bulge 35' to throw outward lever-roller 34 of the mechanism at the finishing-station C, thereby raising the bottle-holder and placing the neck thereof between formers 56 and with plug 54 depending thereinto, this position being maintained until bulge 35' has passed backward over roller 34 and into the position indicated in dotted lines in Fig. 6, 30 when the roller is free to move inward, thereby lowering the bottle-holder. At this juncture arm 69 has reached the limit of its movement (indicated in dotted lines in the same figure) and is ready to advance carrier 6 another step, 35 and as the carrier thus advances all of the under mechanisms connected thereto move with it, including levers 32 and rollers 34. Ring 35 is oscillated at the same time and in the same direction, so that bulge 35' remains 40 between two of rollers 34 and is moved from the dotted to the solid line position (seen in Fig. 6) and in readiness to operate roller 34 of the mechanism then at finishing position C upon the next backward oscillation of ring 35. 45 In operation the unfinished bottles may be placed in the several holders or snaps on the carrier by means of the transfer mechanism shown and described in my former application or in any other convenient manner. 50 The bottles are then advanced step by step beneath the bottomless reheating hood or chamber 71, into which their necks or upper portions project, as shown in Fig. 7. Thus only that portion of each bottle is reheated 55 and softened that requires refinishing, the lower portion being unaffected, so that it is not injured or distorted by the gripping pressure of the snap-sections when held by the latter during the period of rotation at high speed 60 at the finishing position. As each bottle emerges from hood or chamber 71 into finishing position C the bottle is rotated very rapidly for the finishing operation, as at that time the high-speed gear is brought into action through the engagement of lever 24 with bulge 25' of ring 25, and this high speed causes the snap to close and tightly grip the bottle, as above described. The operation of the machine is so timed that a fresh finishing mechanism is turned downward into operative 70 position concurrently with the arrival of a fresh bottle therebeneath. The above-described backward movement of ring 35 then begins, causing bulge 35' to move behind and project outward the roller 34 of lever 32, 75 thereby raising the holder and bottle, with the neck of the latter between formers 56 and surrounding the plug 54. At this instant lever 64 is so operated as to cause rod 66 to engage and hold the finishing mechanism properly 80 centered, and at the same time bar 63 is depressed, causing roller 63' to depress head 58 and close formers 56 around the bottle-neck. Before bulge 35' completes its backward 85 traverse of roller 34 bar 63 is raised and the formers 56 permitted to swing outward, so that when roller 34 drops from engagement with the bulge 35' the bottle-neck is released and free to move downward with the holder. 90 During the finishing operation the several parts rotate very rapidly, and the finishing is accomplished almost instantly, the formers 56 being closed and again opened while the bottle is in raised position, and hence necessarily during the time bulge 35' is moving backward 95 past roller 34. Then while a fresh bottle is being moved into the finishing position C the mechanism above described is operating to turn a fresh forming mechanism into operative position. 100 Projecting from crank 44 is an arm 72, which carries a swab 72', which may be soaked with a solution of oil and charcoal and which is so positioned that as arm 44 moves the mechanism forward for a fresh hold on the 105 finishing-mechanism carrier, as shown in full lines in Fig. 1, the swab is moved inward over and lubricates the plug of the finishing mechanism which is next turned into operative position, thus conditioning the plug for 110 securing the best results and preventing it from sticking to the glass. 115 The necessary pressure of formers 56 on the bottle-neck may have a tendency to distort the same if the glass has been rendered 120 too soft by excessive reheating—a condition difficult to always avoid. To guard against this, I have made provision for admitting air under pressure to the bottle during the finishing operation by forming a duct 54' through 125 plug 54, with which registers duct 73 of stem 53, the latter registering with passage 74, extending through carrier 40 to spindle 39 and adapted when in downturned or operative position to register with passage 75 of spindle 39. Air under pressure may be supplied from a suitable source through the hose connection 76. Thus the shape of the bottle is preserved, the internal air-pressure counteracting any tendency on the part of the in- 130

wardly-pressing external formers to distort the softened glass. While I consider this a desirable feature, the operation of the apparatus is not dependent thereon and the same may be omitted.

5 I claim—

1. In a bottle-finishing machine, neck-forming mechanism having devices for operating on the interior and exterior of a bottle-neck, a series of bottle-holders movable intermittently past the forming mechanism, and means operating while the holders are at rest for causing the neck-forming mechanism and one of the holders to coöperate in finishing a bottle.
- 15 2. In a bottle-finishing machine, an intermittently-movable carrier, neck-forming mechanisms on the carrier and adapted successively to be moved into operative position, each of said mechanisms having devices for operating on the interior and exterior of a bottle-neck, a bottle-holder, and means operating while the carrier is at rest for causing the operative neck-forming mechanism and the bottle-holder to coöperate in finishing a bottle.
- 25 3. A holder for a bottle-finishing machine comprising a rotatable support, and bottle-securing means carried thereby and adapted to be actuated by centrifugal force.
- 30 4. A holder for a bottle-finishing machine comprising a rotatable support, bottle-securing devices hinged thereto, and pivoted weighted arms carried by the support and connected to the bottle-securing devices, the arms being actuated by centrifugal force.
- 35 5. Bottle-finishing mechanism comprising a forming device, a series of bottle-holders movable intermittently past the forming device with one of said holders alining therewith at each pause in the movement of the holders, and means operating while the holders are at rest for raising and lowering the holder alining with the forming device.
- 40 6. Bottle-finishing mechanism comprising a forming device adapted to close and open, a series of bottle-holders movable intermittently past the forming device with one of said holders alining therewith at each pause in the movement of the holders, means operating while the holders are at rest for raising and lowering the holder alining with the forming device, and means for closing and opening the forming device while the holder is raised.
- 45 7. Bottle-finishing mechanism comprising a depending forming device, a series of bottle-holders movable horizontally beneath and in line with said device, means for intermittently moving the holders with one of the same in line with the forming device at each pause in the movement of said devices, and means operating to raise and lower the alining-holder while the holders are at rest.
- 55 8. Bottle-finishing mechanism comprising a depending forming device adapted to close and open around the bottle to be finished, an

intermittently-movable series of bottle-holders beneath and adapted successively to aline with the forming device at each pause in their movement, means operative while the holding devices are at rest for raising and lowering the alining holding device, and means operating while said device is raised for closing and opening the forming device.

9. Bottle-finishing mechanism comprising an intermittently-movable carrier, forming devices on the carrier and adapted successively to be moved thereby into operative position, a bottle-holder, and means for moving the holder toward and from the operative finishing device while said carrier is at rest.

10. Bottle-finishing mechanism comprising an intermittently-movable carrier, forming devices on the carrier and adapted successively to be moved thereby into operative position, the forming devices being adapted to open and close with means for holding them normally open, a bottle-holder movable toward and from the operative forming device while said carrier is at rest, and means for closing said forming device while the bottle-holder is projected toward the same.

11. Bottle-finishing mechanism comprising a rotatable carrier, forming devices rotatably mounted in the carrier and adapted successively to be moved thereby into operative position, rotating means common to all of said devices and operating to rotate each one while in operative position, and bottle-holding means.

12. Bottle-finishing mechanism having an intermittently-rotatable carrier, a series of forming devices rotatably mounted in the carrier and adapted successively to be moved thereby into operative position, each of the forming devices being adapted to open and close with means for holding the same normally open, mechanism for rotating the forming devices, a bottle-holder movable toward and from the operative forming device, and means for closing and opening said devices while the bottle-holder is projected toward the same.

13. Bottle-finishing mechanism comprising an intermittently-rotatable carrier, neck-forming devices arranged radially thereon in such manner that two of the devices aline through the center of the carrier, the devices being adapted successively to be moved by the carrier into operative position, bottle-holding means, and means adapted to coöperate with the forming device alining with the active forming device for holding the latter in proper position.

14. Bottle-finishing mechanism comprising a rotatable carrier, a series of neck-forming devices on the carrier, means for intermittently rotating the carrier for moving the forming devices successively into operative position, an intermittently-movable series of bottle-holders movable simultaneously with said carrier, and means operating while said carrier is at rest for raising and lowering the alining holding device, and means operating while said device is raised for closing and opening the forming device.

carrier and holders are at rest for causing the operative forming device and one of the bottle-holders to coöperate in finishing a bottle.

15. In a glass-finishing machine, forming mechanism adapted to bear inwardly upon and shape the exterior surface of an article, and means for admitting air into the article to resist distortion thereof due to the pressure of the forming mechanism.

16. In a glass-finishing machine, forming mechanism adapted to bear inwardly upon and shape the exterior surface of an article, interior shaping means, and means for admitting air into the article to resist distortion thereof due to the pressure of the exterior forming mechanism.

17. In a glass-finishing machine, a device adapted to fit within and shape the interior of the mouth or neck of the article, the device having an air-passage, forming devices adapted to close and bear upon the exterior surface of the article, and means for admitting air into the article through the interior shaper for resisting distortion due to the pressure of the exterior formers.

18. Glass-finishing mechanism comprising an intermittently-rotatable carrier, a series of shaping devices on the carrier adapted, successively, to be moved thereby into operative position, each of said devices including a tubular plug which enters the neck or mouth of the article being finished, air-passages extending from each of said plugs to the axial center of the carrier, and an air-passage opening through the carrier-axis with which the passages of the carrier are adapted to register as each finishing device is moved into operative position.

19. In a bottle-finishing machine, heating means, mechanism for finishing the inner and outer surfaces of a bottle-neck, and a bottle-carrier adapted to present a bottle to the heating means before it is operated on by the finishing mechanism.

20. In a bottle-finishing machine, heating means, bottle-finishing mechanism consisting of interior and exterior forming devices adapted to operate on the inner and outer sur-

faces of a bottle, and a bottle-carrier adapted to present the bottle to the heating means before it is operated on by the finishing mechanism.

21. In a bottle-finishing machine, neck-forming mechanism and a bottle-carrier adapted to coöperate by a movement in the direction of the bottle-axis, and heating means to which the bottle is presented by the carrier before it is operated on by the forming mechanism.

22. In a glass-finishing machine, heating means, finishing mechanism, and a carrier movable past the heating means and finishing mechanism and adapted to present the article to the heating means in advance of the finishing mechanism.

23. In a bottle-finishing machine, heating means, neck-finishing mechanism operating from above and adapted to operate on an upright bottle, and a carrier adapted to hold a bottle upright and present it to the heating means before it is operated on by the finishing mechanism.

24. In an automatic bottle-finishing machine, the combination of bottle-neck-heating means, automatic intermittently-operating neck-finishing mechanism, and an intermittently-movable bottle-holder adapted to present the bottle first to the neck-heating means and then into position to be finished.

25. In an automatic bottle-finishing machine, the combination of a bottomless reheating-chamber, automatic intermittently-operating neck-finishing mechanism, an intermittently-movable bottle-holder adapted to sustain the bottle in upright position and first move it beneath the reheating-chamber and then move the bottle into position to be finished, and means operating at said position for causing the finishing mechanism to engage the bottle-neck.

In testimony whereof I affix my signature in presence of two witnesses.

FRANK O'NEILL.
